UNITED STATES PATENT OFFICE

130,306

DESIGN FOR A COMBINED PERFUME HOLDER AND STUD BUTTON

Amson Furtsch, New York, N. Y.

Application August 20, 1941, Serial No. 102,971

Term of patent 3½ years

To whom it may concern:

Be it known that I, Amson Furtsch, a citizen of the United States, residing in the city, county, and State of New York, have invented a new, original, and ornamental Design for a Combined Perfume Holder and Stud Button, of which the following is a specification, reference being had to the accompanying drawing, forming a part thereof, in which:

Fig. 1 is a side elevational view of a combined perfume holder and stud button showing my new design;

Fig. 2 is a top plan view thereof; and

Fig. 3 is a vertical cross-sectional view showing particularly the pad containing the perfume.

The dominant feature of the present design is the provision of a cup-shaped holder having in the bottom thereof an absorbent pad which retains the perfume and a perforated cover closing the top of said cup.

I claim:

The ornamental design for a combined perfume holder and stud button, substantially as shown and described.

AMSON FURTSCH.
